LOCK WASHER

Carl G. Olson, Chicago, Ill., assignor to Illinois
Tool Works, Chicago, Ill., a corporation of
Illinois

Application February 27, 1933, Serial No. 658,738

8 Claims. (Cl. 151—35)

My invention relates generally to locking devices and particularly to locking devices or washers of the pronged type, namely, the type provided with radial prongs along one margin of an annular body.

One of the primary objects of my invention is to provide a locking device of improved practical construction, which may be readily formed from flat spring stock.

More specifically, my invention contemplates the provision of a locking device equipped with warped prongs which are configurated in a novel manner so as to improve the locking characteristic thereof, and to this end I propose to so shape and warp the prong that a curved locking edge will project above and below the plane of the washer body so as to aggressively engage the work piece and the surface of a nut or screw head to thereby positively secure said parts against relative movement.

Still more specifically, my invention contemplates the provision of prongs provided along at least one margin of an annular body of flat stock, which prongs are so warped, twisted, or flexed out of the plane of the body to present edges which partake of a reverse curvature in extending from the body to the free extremity of the prong.

A further object of my invention contemplates the provision of a locking device, as set forth above, in which the locking edges of the prongs projecting on opposite sides of the washer body are so curved that the portion of the edge in the vicinity of the free extremity of the prong is tangent to a line parallel with the plane of the washer body, and in this manner I present locking edges as distinguished from sharp work engaging corners, said edges extending over a radial distance which is sufficient to effectively resist retrograde movement of the screw head or nut clamped thereagainst.

It has been found that in some instances a locking edge, as distinguished from a sharp work engaging corner, is preferable. Sharp work engaging corners have a tendency to mill a groove in the work. This is particularly true in instances where a nut or screw head must be loosened from time to time. When the nut is loosened by the application of considerable force, the sharp work engaging corners of the prongs in opposing retrograde movement causes a groove of V-shaped cross section to be milled or formed upon the clamping surface.

It is an object of my invention to provide a locking edge which will not produce the above

mentioned milling or grooving effect, and to this end I propose to produce a locking edge which does not extend over the greater portion of the radial length of the prong, but which, due to its curvature, will imbed itself within the work with an effectiveness equal to or greater than a straight locking edge of greater length.

The foregoing and numerous other objects and advantages will be more apparent from the following detailed description when considered in connection with the accompanying drawing, wherein—

Figure 1 is a plan view of a locking device or washer constructed in accordance with the teachings of my invention;

Figure 2 is a transverse sectional view taken substantially along the line 2—2 of Figure 1, a work piece and nut being indicated by dotted lines in operative association with the washer;

Figure 3 is an enlarged view of the prong shown at the left side of Figure 2;

Figure 4 is similarly an enlarged fragmentary view of the central prong of Figure 2, said view being taken along the line 4—4 of Figure 1;

Figure 5 is an enlarged plan view of the prong shown in Figure 4;

Figure 6 is a fragmentary plan view of a washer provided with my improved prong construction along the outer margin of the body, as distinguished from the internal tooth construction shown in Figures 1 and 2; and

Figure 7 is a plan view of an electrical terminal which is provided at one extremity with my improved prong construction.

Referring now to the drawing more in detail wherein like numerals have been employed to designate similar parts throughout the various figures, it will be seen that my invention contemplates a locking device or washer, which includes an annular body 10 and a plurality of radial prongs 12 formed and spaced along the inner margin thereof (see Figures 1 to 5, inclusive). It will be seen that each of the prongs 12 is warped or twisted in such a manner as to present work engaging edges 14 on opposite sides of the plane of the washer body 10. Each prong is substantially rectangular in cross section and is preferably of slightly greater thickness at the root than at the free extremity thereof. However, the taper of the tooth is very slight.

It will be observed that the edges 14 (see particularly Figure 3) partake of a reverse curvature. That is to say, the outer portion of the edge, namely, the portion A positioned toward the free end of the prong, has a curvature reverse to the

curvature of the edge where it joins the body 10, namely, the portion B. It will be seen that the work engaging portion A (Figure 3) of the edges 14, positioned in the vicinity of the free extremity 5 of the prong, is tangent at its outermost point to a line 16, and this line is substantially parallel with the plane of the washer body 10. The portion B (Figure 3) of the curvature positioned at the root of the prong is tangent to a line 18 which 10 is coincident with the plane, which includes one of the bounding surfaces of the body 10.

The portion A of each edge 14 is adapted to imbed itself within the clamping surface of the nut 18 and work piece 21 in a very effective manner. The curvature of this portion A materially assists in causing the edge to more readily imbed itself than a straight edge of equal or greater length. In other words, if the edge 14 were straight over a greater portion of the radial 20 length of the prong, it would require greater clamping force to cause said edge to imbed itself than when the relatively short curved section A is employed. The action of the portion or section A upon the adjacent surface of the work or nut 25 differs materially from the action of a sharp work engaging corner. That is to say, if the line 14 of Figure 3 curved out of the plane of the washer body until it terminated at the free end of the prong, a sharp three-sided corner would be presented. Such a corner, while it readily imbeds itself within the work and nut and serves to secure the parts against relative movement, has a tendency in some instances to cause a groove of V-shaped cross section to be formed or milled within 30 the surface of the nut. This is particularly true when the washer is used in combination with a nut or screw head which must from time to time be loosened for purposes of replacement or repair. In loosening the nut or screw, the opposition afforded by the sharp work engaging corner is sufficient to cause a groove to be formed. Then, when the nut or screw is again applied to the washer, the locking effectiveness of the teeth is 40 materially reduced. By employing prongs of my improved construction, wherein a relatively short but effective section of a curved edge projects out of the plane of the washer body, this milling or grooving action is materially reduced without impairing but rather increasing the locking effectiveness of the prong.

The cross section of the prong is substantially rectangular, and an effective strutting action, as indicated by the dot-and-dash line in Figure 4, takes place between the oppositely disposed edge 55 sections A.

It will be apparent that the invention is not limited to the washer shown in Figure 1, wherein the teeth or prongs are provided along the inner margin, but is also capable of application in the 60 type of washer shown in Figure 6, wherein prongs 12a are provided along the external margin of an annular body portion 10a. Likewise, my improved prong construction may be used on devices, such as the electrical terminal 20 shown in Figure 7. 65 This terminal includes a body portion 22 and is provided at one extremity with an aperture 24 for receiving the free end of an electrical conductor, and is formed at its opposite end with a plurality of prongs 12b, which correspond structurally with the prongs 12 shown in Figures 1 to 5, inclusive.

From the foregoing it will be apparent that my washer presents a marked improvement over washers of this general type which have been employed heretofore, in that the arrangement of the 70 work engaging edges is such as to present a curved

line engagement. The curvature of the edge contributes materially toward its effectiveness in imbedding itself within the surface of the work with a minimum amount of clamping force, and also precludes the deleterious milling or cutting effect 80 previously referred to. While I have herein disclosed a specific curvature in the edge of the prong, it should be understood that the invention is capable of other modifications and changes without departing from the spirit and scope of 85 the invention.

Having thus described my invention, what I claim as new and desire to secure by Letters Patent is:

1. A locking device including an annular body 90 portion formed from flat spring stock and a plurality of radially extended prongs provided along at least one margin thereof, said prongs being warped so as to present radially disposed work engaging edges on opposite sides of the plane of the body portion, the sections of said edge in the vicinity of the free extremity of the prong being curved and providing an effective locking medium when clamped between two surfaces. 95

2. A locking device including an annular body 100 portion formed from flat spring stock and a plurality of prongs provided along at least one margin thereof, said prongs being warped so as to present work engaging edges on opposite sides of the plane of the body portion, the sections of said edge in the vicinity of the free extremity of the prong being curved and providing an effective locking medium when clamped between two surfaces, 105 said curved portion having a length which is not greater than half the radial length of the 110 prong.

3. A locking device including an annular body portion formed from flat spring stock and a plurality of radially extended prongs provided along at least one margin thereof, said prongs being 115 warped so as to present radially disposed work engaging edges on opposite sides of the plane of the body portion, the sections of said edge in the vicinity of the free extremity of the prong being curved and providing an effective locking medium when clamped between two surfaces, one point on said curved section being coincident with a tangent parallel with and spaced from the plane of the body. 120

4. A locking device including an annular body 125 portion formed from flat spring stock and a plurality of radially extended prongs provided along at least one margin thereof, said prongs being warped so as to present radially disposed work 130 engaging edges on opposite sides of the plane of the body portion, each edge including sections curved in opposite directions, one of said sections being located in the vicinity of the free extremity of the prong in position to lockingly engage a work piece when clamped thereagainst. 135

5. A locking device including an annular body portion formed from flat spring stock and a plurality of radially extended prongs provided along at least one margin thereof, said prongs being warped so as to present radially disposed work 140 engaging edges on opposite sides of the plane of the body portion, said edge including sections curved in opposite directions, one of said sections being located in the vicinity of the free extremity of the prong in position to lockingly engage a work piece when clamped thereagainst, another portion of said curved edge in the vicinity of the root of the prong blending with one of the bounding surfaces of the body portion. 145

6. A locking device including an annular body 150

- portion formed from flat spring stock and a plurality of radially extended prongs provided along at least one margin thereof, said prongs being warped so as to present radially disposed work 5 engaging edges on opposite sides of the plane of the body portion, said edge including sections curved in opposite directions, one of said sections being located in the vicinity of the free extremity of the prong in position to lockingly engage a work piece when clamped thereagainst, another portion of said curved edge in 80 the vicinity of the root of the prong blending with a tangent coincident with a plane which includes one of the bounding surfaces of said body portion.
- 10 8. A locking device including an annular body portion formed from flat spring stock and a plurality of radial prongs spaced along at least one margin thereof, said prongs being twisted from their roots to their free ends so as to present work engaging edges on opposite sides of the plane of the body portion, the sections of each edge in the vicinity of the free extremity of the prong being curved and providing an effective locking medium when clamped between two surfaces.
